UNITED STATES PATENT OFFICE

BERTHA SAUNDERS, OF HOLLYWOOD, CALIFORNIA

HAIR WAVER

Application filed October 19, 1931. Serial No. 569,651.

This invention relates to a hair waver, and more particularly pertains to a permanent waving appliance of the character set forth in my copending application for United States patent, Serial Number 541,354, filed June 1, 1931, and of the type used in connection with various kinds of permanent wave equipment.

An object of the invention is to provide a hair waver which may be employed in a particularly efficacious manner to produce the highly desirable flat and natural wave rather than the coiled or curly wave such as ordinarily formed with permanent wave equipment.

Another object is to provide a construction in hair wavers whereby the hair after being wrapped thereon in a sinuous formation may be stretched and maintained under tension throughout the length of the wound portion thereof during heat treatment thereof, to insure the formation of a well defined and lasting "permanent" wave.

Another object is to provide in the waver a formation which insures the retention in place of the hair wound thereon.

Another object is to provide a waver of the character described which is of simple and inexpensive form and capable of having the hair quickly and easily wrapped thereon to produce the aforesaid flat wave.

A further object is to provide a hair waver of the character described which is capable of use with various types of permanent wave heaters without necessitating changing the construction of the heaters and associated equipment thereof.

Yet another object is to provide a waver of the character which is constructed in such manner as to permit of wrapping the hair thereon in various ways whereby to produce flat waves of differing styles or to produce coiled waves, as desired.

Still a further object is to provide a hair waver of the character described on which the hair is wound and maintained in such manner as to more evenly and effectively subject it to the action of the heat of the permanent wave equipment with the result that a more lasting and better wave is produced.

With the foregoing objects in view, together with such other objects and advantages as may subsequently appear, the invention resides in the parts and in the combination, construction and arrangement of parts hereinafter described and claimed and illustrated by way of example in the accompanying drawings, in which:

Figure 1 is a plan view of the hair waver as constructed to be extendable, and showing it in its normal position;

Figure 2 is a plan view of the hair waver shown in Figure 1, illustrating it in its extended position;

Figure 3 is a view in longitudinal section as seen on the line 3-3 of Figure 2;

Figure 4 is a detail in cross section taken on the line 4-4 of Figure 1;

Figure 5 is a detail in longitudinal section as seen on the line 5-5 of Figure 1;

Figure 6 is a view in cross section taken on the line 6-6 of Figure 5;

Figure 7 is a view in cross section taken on the line 7-7 of Figure 5;

Figure 8 is a view in cross section taken on the line 8-8 of Figure 5;

Figure 9 is a view in end elevation of the structure shown in Figure 5;

Figure 10 is a plan view of the hair waver as when extended, and showing the hair thereon;

Figure 11 is a view of a modified form of the invention;

Figure 12 is a longitudinal section taken on the line 12-12 of Figure 11;

Figure 13 is a cross section taken on line 13-13 of Figure 11;

Figure 14 is a plan view of the waver shown in Figure 11, showing the manner of winding hair thereon.

The hair waver considered generally embodies a body portion comprising two elongated members or plates A and B here shown as of substantially concavo-convex or V-shaped cross section and nested one upon the other. Each of the plates A and B is provided along its longitudinal edges with spaced arcuate notches or recesses 15 and 16 defining on said edges rows of spaced substantially dove-tail shaped pro-

jections 17 and 18 constituting wave forming members on the body portion each of which consists of two sections. The projections 17 of each of the plates are out of line with projections 18 whereby a staggered arrangement of the recesses and projections is produced and whereby the hair to be waved may be wound progressively along the body portion over the projections 17 thence over adjacent projections 18 and so on in a sinuous formation throughout the length of the body portion. As shown in Figure 1, the two plates are normally held so that the notches and projections register with one another, but upon moving one plate relative to the other the projections or wave forming members are moved relative to each other out of registration, as indicated in Figure 2, and this provides for stretching the hair as will be hereinafter described.

At certain corresponding ends the plates A and B are provided with axially extended projections 19 which are slotted and facilitate securing strands of hair to the waver with a cord or string, as shown in Figure 10. The other corresponding terminals of the plates A and B have similar extended projections 20 and 21 thereon which provide for holding the plates together and for adjusting the plates in order to stretch the hair thereon and which projections 20 and 21 afford a means for securing the outer ends of the strands of hair to the waver together with the cord or string.

Fixed to the projection 20 of the plate A near the inner end thereof is a collar 22 having a bore of sufficiently great diameter to slidably accommodate the projection 21 of the plate B, as shown in Figure 5. Rotatably telescoping both projections is a tubular handle and adjusting member 23, the inner end of which engages in an annular recess 24 in the collar 22. A portion of the bore of the member 23 is screw threaded, as at 25, and cooperates with threads 25' formed on the projection 21 whereby to move the latter and the plate B relative to plate A, upon turning the member 23.

Mounted and frictionally held in the tubular member 23 is a helically coiled spring 26 which acts as a continuation of the screw threads 25 of said member. In assembling the waver the member 23 with the spring 26 therein is mounted on the projections 20 and 21 and turned so as to screw onto the threads 25' of the projection 21 until the inner end of member 23 engages in the recess 24 in the collar 22. It is noted that the spring 26 will also screw onto the threads 25'. Next, a washer 27 is forced into the member 23 against the outer end of the spring and is secured on the projection 20 by means of a pin 28. Openings 29 in the member 23 facilitates insertion and removal of the pin, which, when in place, holds the spring under tension

and thereby maintains the member 23 in engagement with the collar 22.

When the waver is arranged as shown in Figure 1 it is ready to have the hair wound thereon, and the method of winding the hair is varied depending on the type of wave desired. After the hair is wound on the waver, it is desirable to stretch the hair and place it under tension, especially during the heat treatment, in order to increase the effectiveness of the wave and produce a more lasting wave treatment of the hair. To so stretch the hair the operator merely rotates the member 23 in the appropriate direction and thereby causes the plate B to move longitudinally of the plate A. Inasmuch as the plates are normally arranged with the recesses and projections in registration, it is seen that movement of one plate relative to the other will cause the parts to assume the out-of-line position shown in Figures 1 and 10 and the strand of hair wound on the waver will therefore be stretched and held under tension as aforesaid. After the waving operation the operator may readily restore the waver to the normal position by rotating member 23 until the notches and projections of the plates A and B come into registration, as shown in Figure 1.

One way of winding the hair in order to produce the highly desirable and popular flat wave is to secure the strand of hair at a point close to the head, to the end projections 19 by means of the cord or string, as shown in Figure 10, then wrap the strand under the end projections 17 and then over the upper side of projections 18, then under the web portions C between said projections and over the upper side of the next pair of projections 17 and so on until the waver is covered, as shown in Figure 10. The end of the hair strand is then tied as at D and the usual hair waving operation is then carried out, it being noted that the waver will fit various kinds of permanent waving heaters.

It should be noted that the waver is held with the concave sides of the plates A and B uppermost during the winding of the hair thereon, as the edges of recesses 15 and 16 are then downwardly inclined towards the longitudinal medial line of the said plates. Such inclination causes the hair strand to slide easily towards the inner sides of said recesses and also aids in holding the strand in such position inasmuch as lateral displacement of the strands is then checked by the edges of said recesses. Furthermore, the V-shaped cross section facilitates the nesting of the plates A and B and the holding thereof in properly assembled relation. The arcuate recesses 15 and 16 are in effect nearly circular openings which open on the longitudinal edges of the plates A and B. This form of recess not only provides a large space for the proper accommodation of the thick

strands of hair but produces a hook effect in that the projections 17 and 18 defined between said recesses are of dove-tail shape. Such shape in the projections insures the holding of the wound portions of the hair in a tight compact wrapping and prevents lateral bulging or slipping of the coils or windings of the hair strand.

It is important to note that regardless of the type of heater, not shown, used to treat the hair wound on the waver of this invention, the member 23 will extend outwardly where it may be readily grasped and turned to stretch the hair as aforesaid during the heat treatments or waving operation, without necessitating removal of the waver from the heater or in any way interfering with the heat treatment.

The variational form of the invention shown in Figures 11 to 14, inclusive, comprises a single body portion 30 corresponding in shape and formation to either of the plates A and B and having staggered dove-tail projections 31 and 32. This form is the same as in my previous application except that it is of V-shape in cross section to provide the advantage previously mentioned, and has the dove-tail projections to insure an effective close winding of the hair thereon.

Thus it is seen that either the plate A or B of the first described form of my invention may constitute the variational form shown in Figures 11 to 14, inclusive. This variational form is adapted to have the hair wound thereon in the same manner as the first described form of this invention and will provide all of the advantages of the first described form except the stretching of the hair.

I claim:

1. In a hair waver, a pair of elongated plates mounted one upon the other, a plurality of spaced projections on each of said plates providing for the winding of hair thereon, and means at certain ends of said plates for holding said plates together and for moving one plate longitudinally relative to the other whereby to stretch the hair wound on said plates.

2. In a hair waver, a pair of elongated members mounted one upon the other, a plurality of spaced projections on longitudinal edges of said members, and means at certain ends of said members for holding said members together and for moving one member longitudinally relative to the other member.

3. In a hair waver, a pair of elongated members mounted one upon the other and having normally registering notches opening on longitudinal edges thereof, said notches being adapted to receive strands of hair wound around said members, and means operative at certain ends of said members for moving one member relative to the other

to dispose the notches out of alignment whereby to stretch the hair wound on said members.

4. In a hair waver, a pair of elongated members mounted one upon the other and having normally registering notches opening on longitudinal edges thereof, said notches being adapted to receive strands of hair wound around said members, means operative at certain ends of said members for moving one member relative to the other to dispose the notches out of alignment whereby to stretch the hair wound on said members, said means including terminal portions on said members, one of which portions is screw threaded, a collar fixed on the other terminal portion, a tubular member rotatably surrounding said terminal portions and engaging said collar, said tubular member having screw threads therein engaging the screw threads of said terminal portion, and means holding said tubular member against axial movement relative to said terminal portions.

5. In a hair waver, elongated members having spaced notches in longitudinal edges thereof to receive strands of hair wound on said members, means for holding said members one upon the other with the notches of one member in registration with the notches of the other member and for moving one member relative to the other whereby to move the notches out of alignment.

6. In a hair waver, elongated members having spaced notches in longitudinal edges thereof to receive strands of hair wound on said members, means for holding said members one upon the other with the notches of one member in registration with the notches of the other member and for moving one member relative to the other whereby to move the notches out of alignment, said members being substantially V-shaped in cross section.

7. In a hair waver, elongated members having spaced notches in longitudinal edges thereof to receive strands of hair wound on said members, means for holding said members one upon the other with the notches of one member in registration with the notches of the other member and for moving one member relative to the other whereby to move the notches out of alignment, said members being substantially V-shaped in cross section, and said notches being of substantially circular formation.

8. In a hair waver, elongated members having spaced notches in longitudinal edges thereof to receive strands of hair wound on said members, means for holding said members one upon the other with the notches of one member in registration with the notches of the other member and for moving one member relative to the other whereby to move the notches out of alignment, said members being of concavo-convex form.

9. In a hair waver, an elongated plate having spaced notches opening at a longitudinal edge thereof and adapted to receive strands of hair wound on said plate, said plate being substantially V-shaped in cross section throughout the length thereof. 70
10. In a hair waver, elongated members mounted one upon the other and having notches therein to receive strands of hair, terminal portions on said members, one of which terminal portions is screw threaded, a tubular adjusting member telescoping said portions and having internal screw threads engaging the threads on said portion, a collar on the other terminal portion engaging the inner end of said tubular member, a coiled spring frictionally engaged within the bore of and arranged to rotate with the tubular member and to thread upon the screw threads of said terminal portion, and a member fixed on the other terminal portion and engaged and holding said spring under tension and within said tubular member. 75
11. In a device for waving the human hair, members having relative longitudinal movement and provided with aligned lateral arms, and a handle journaled on one of said members and threaded upon the other of said members, to produce relative longitudinal movement between said members, and to move the arms out of alignment. 80
12. In a device for waving the human hair, stem members disposed side by side, each stem member having arms which project laterally in opposite directions, the arms being spaced apart longitudinally of the stem members, whereby a strand of hair can be looped in opposite directions about adjoining, oppositely-projecting arms, and be extended diagonally across one of the stem members between adjoining arms, means for connecting the stem members for relative longitudinal movement, and means for producing relative longitudinal movement between the stem members, to move the arms of one stem member toward and from alignment with the arms of the other stem member. 85
13. In a hair waver, a body portion, a plurality of spaced wave forming members on said body portion, each member comprising two sections one of which is movable relative to the other, and means for so moving said movable sections. 90
14. In a hair waver, a body portion, a plurality of spaced wave forming members on said body portion, each member comprising two sections one of which is movable relative to the other, means for so moving said movable sections, and means independent of said members for securing the hair to the body portion adjacent the ends of the latter. 95
15. In a hair waver, a body portion comprising a pair of connected plates movable longitudinally relative to each other, a wave forming projection on said body portion comprising a pair of members one of which is carried on one of said plates and the other of which is carried on the other of said plates, and means for moving said plates longitudinally in opposite directions relative to each other to effect stretching of a strand of hair wound around said projection. 100
